APPARATUS FOR CEMENTING SOLES ON
SHOESJoseph Amico, Rochester, N. Y., assignor to
Frank Keiper, Rochester, N. Y.

Application November 12, 1938, Serial No. 240,085

14 Claims. (Cl. 12—33)

The object of this invention is to provide a machine or an apparatus for cementing soles on shoes.

Another object of the machine or apparatus is to provide a uniform pressure over the whole area of the sole while the cement is taking hold or setting.

Another object of the invention is to provide a new and improved electrical unit for heating the sole while it is being applied to the shoe.

Another object of the invention is to provide a head containing the pressure and heating units at the top of the machine, against which the sole of the shoe is pushed upwardly while the shoe is in an inverted position.

Another object of this invention is to make this unit so that it will secure uniform pressure and heating effect on the sole of the shoe.

Another object of the invention is to provide an apparatus that is adapted to be used in cementing soles on shoes of widely different sizes and shapes.

Another object is to provide adjustments that will accommodate the apparatus to shoes of widely different sizes and shapes.

Another object of the invention is to provide a heating unit and a thermostat control external thereto and remote therefrom that will limit the heating effect of the electric current on the heating unit.

These and other objects of the invention will be illustrated in the drawings, described in the specification, and pointed out in the claims at the end thereof.

In the drawings:

Figure 1 is a side elevation of the machine with the lower part partly broken away to expose the moving parts.

Figure 2 is a top plan view of the machine with the head in its closed or lowest position, with the shoe omitted and the head to the left of the position shown in Figure 3.

Figure 3 is a sectional view of the machine, the section being taken on the line 3x—3x of Figure 2, the lower part of the machine being broken away and the shoe and its support being shown in its lowest or initial position, corresponding to the position shown in Figure 1, with the head in the position to the right of the position shown in Figure 2 and with the shoe and last in position.

Figure 4 is a side elevation of the upper part of the machine, with the head partly broken away, with the shoe and jack raised to its ultimate position.

Figure 5 is a section on the line 5x—5x of Figure 4.

Figure 6 is a top plan view of the rubber cushion plate used in the head.

Figure 7 is a bottom plan view, partly broken away, showing the heating unit of the head.

Figure 8 is a section on the line 8x—8x of Figure 3.

Figure 9 is a transverse section on the line 9x—9x of Figure 5, showing the lower portion of the head or housing and the horseshoe plate for holding the rubber cushion pads in place.

Figure 10 is a section on the line 10x—10x of Figure 1.

Figure 11 is an end view of the head, looking at it from the right in Figures 2 and 3.

Figure 12 is a top plan view of a modified form of the rubber cushion plate otherwise shown in Figure 6.

Figure 13 is a cross section of the cushion plate shown in Figure 12, the section being taken on the line 13x—13x of Figure 12.

Figure 14 is a diagrammatic view of the electrical connections.

Figure 15 is a bottom plan view of the left shoe, with a support for the welt thereof, a man's size shoe being shown.

Figure 16 is a side elevation of the shoe and the support for the welt thereof shown in Figure 15.

Figure 17 is a top plan view of the welt support shown in Figures 15 and 16.

Figure 18 is a section through the right hand end of the welt support shown in Figures 15 and 16, the section being taken on the line 18x—18x of Figure 16 and the rest of the support being broken away.

Figure 19 shows a section on the line 19x—19x of Figure 17, the scale being enlarged.

Figure 20 shows a section on the line 20x—20x of Figure 17, the scale being enlarged.

In the drawings like reference numerals indicate like parts.

In the drawings reference numeral 1 indicates a pedestal having a base 2, both of which are hollow, the pedestal being open at the top and bottom. On the top of the pedestal is a plate 3 which has a boss 4 and 5 extending downwardly and upwardly therefrom, as shown in Figure 3. This plate is fastened to the top of the pedestal by screws 6, 7, 8, and 9, as shown in Figure 2, and by screws intermediate of the plate which are not shown.

On the plate 3 is fastened a pedestal 10, which pedestal is fastened to the plate 3 by screws 11.

which are inserted through the plate from below. The pedestal 10 is expanded at the top to form a head 12 having the horizontal grooves 13 and 14 formed therein. On top of the pedestal 10 is mounted a bearing block 15, the lower edge of which has flanges 16 and 17 thereon which engage in the grooves 13 and 14. This bearing block slides freely forward and back in the grooves 13 and 14 and its travel is limited as follows: In the flange 16 on one side is formed a long recess 18, the length of which is shown in Figure 3, and the shape of it is shown in cross section in Figure 8. Into this groove extends a screw 19, which loosely engages in the groove and against which the shoulders 20 and 21 on the ends of the flange 16 at either end of the groove abut, and by which the forward and back movement of the bearing block on the head 12 is limited. When the screw 19 is removed, the bearing block may be removed from the head 12 and pedestal.

At the top of the bearing block is formed a bearing which is adapted to support a bolt 22. Pivoted on this bolt is the hollow head 23, which has the shape of an inverted shell. This head is provided with arms 24 and 25 which engage on either end of the bolt and on each side of the bearing head 15. This bolt is fastened in place by the set screw 26, which keeps it from turning. The end of the bolt is provided with a groove 27. On the lower end of the bolt, as shown in Figure 2, is provided a helical spring 28, one end of which engages in the groove 27 and the other end of which engages in the head, as indicated at 29. The object of this spring is to lift or assist in lifting the head 23 on the pivot bolt 22, so that it can be easily swung up from the lower position shown in Figure 3 to the upper position shown in Figure 1, in both of which positions it is locked by a bolt 30 which engages in sockets 31 and 32 formed in the bearing block 15.

In its lowest position this bolt engages with the socket 32 and in its highest position it engages with the hole 31 by which it is locked in its highest position, it being understood that the socket 31 is shown in Figure 2 and the socket 32 is shown in Figure 3. The bolt 30 can be moved longitudinally in the head by the pivoted handle 33, which handle is provided with the hubs 34 and 35 on either side thereof, in which hubs are provided recesses 36. On the forward end of the bolt 30 is mounted a pin 37 extending laterally on each side thereof and engaging with these recesses and by which the bolt can be moved forward or back on the swinging of the handle 33. A hollow space 38 is provided in the head in which is provided a helical spring 39 surrounding the bolt 30. This spring presses against a pin 40 carried on the bolt and normally serves to push the pin to the left in Figure 3, or into the position making locking engagement with the sockets 31 or 32 on the bearing head 15. The movement of the handle 33 upward from the position shown in Figure 3 draws the bolt 30 out of locking position and also lifts the head from the position shown in Figure 3 to the position shown in Figure 1, in which position it is again locked by the engagement of the bolt 30 with the socket 31, it being understood that due to the lifting effect of the spring 28 but little muscular effort is required to lift the head or pull it down again.

As above stated, the head 23 is hollowed out on the under side so as to form a hollow shell. 75

On the under side, as shown in Figure 3, is provided a series of downwardly extending projections or lugs 41. The location of these lugs corresponds to the position of similar lugs 42 formed on the rubber cushion pad or plate 43, the position of which lugs 42 is shown by small circles on Figure 6. As shown in Figure 6, 32 of these circles appear, it being understood that 32 of these lugs are formed on the rubber cushion pad or plate 43 and 32 of these lugs 41 are formed in the hollow head to correspond, which head is made preferably of aluminum and is a single casting.

Projecting inwardly from the sides of the hollow head are the ribs 44, 45, 46, 47, and 48, between which engages the edge of the rubber cushion plate 43 with a sliding engagement and by which it is held in position, and between it has a limited up and down movement. Between the lugs 41 and 42 is provided helical springs 49, 32 of which are used, spaced or positioned to correspond with the small circles in Figure 6. These springs are made preferably of bronze wire and are preferably all alike. This plate is normally convex on top and convex on the bottom, as is shown in cross section in Figure 5. It is hollowed out lengthwise at the right in Figure 3, or at the heel end, to accommodate the steel shank of the shoe. Its shape at the right hand end is shown in Figure 11.

Below the rubber cushion plate 43 is provided the heating unit 50, which consists of a flexible rubber plate having an electrical heating element contained therein and also having a metallic grid contained therein. The electrical heating element is made of a stock high-resistance wire of suitable diameter coiled into a helical coil and is laid in the rubber in the shape indicated in dotted lines in Figure 7 and is vulcanized therein. This wire is indicated by the reference numeral 52.

Suitably spaced from the resistance wire is a metallic grid made up of strips of thin spring steel about $\frac{1}{16}$ of an inch wide. As shown in Figure 7, 32 of these strips are laid crosswise parallel to each other, and these strips are indicated by the reference numeral 53. These strips are spaced about $\frac{1}{8}$ of an inch apart. Across these strips and running lengthwise of the heating unit are similar parallel strips of spring steel, five of which are used, and these strips are indicated by the reference numeral 54. The strips 54 make contact with the strips 53, so that heat will flow and be evenly distributed throughout the grid. 55

The heating wire and the strips 53 and 54 are all molded together in the rubber plate 50, three layers of rubber being used to make the heating plate 50, the heating wire being vulcanized between the first and second layers and the spring steel grid being vulcanized between the second and third layers, and all constituting a single plate with the first layer on the bottom and the third layer on top. In longitudinal cross section this plate 50 is normally shaped as is shown in Figure 3, and in transverse section is substantially straight in cross section. Under pressure this plate 50 conforms as near as may be to the shape of the under side of the plate 43. The springs 49 and these two plates 43 and 50 are assembled into the head, and are all held in place by the horseshoe plate 55, which is fastened to the ends of the ribs 44, 45, 46, 47, and 48 by screws, as is shown in Figures 3 and 9.

Inside of the pedestal 1 is pivotally mounted

a lever 60 having a treadle 61 on the lower outer end thereof. This treadle rocks on a bearing 62. This treadle carries a lug projecting downwardly therefrom, on which is a bearing 63 to which is connected a link 64 which is moved forward and back by the rocking of the treadle 61 on its bearing. Pivotally mounted on the lever 60 is a pawl 65. The lower end of this pawl is connected to the link 64 and is moved back and forward on the pivot 66 by the rocking of the pedal 61. The pawl 65 engages with the ratchet teeth 67 formed on the inside of the pedestal, and by these ratchet teeth the lever 60 can be stopped in any one of four positions as indicated by the four teeth. The pawl 65 is U-shaped and the ratchet has two sets of teeth, of four teeth in each set, with which the two upper ends of the pawl engage. This is shown in Figure 10.

Mounted to slide in the bosses 4 and 5, shown in Figure 3, is the stem 70. This stem is kept from turning by means of the spline 71, which permits a free up and down movement to the stem 70 and holds it against turning. On the stem 70 is fastened a collar 72. The stem passes through a plate 73 supported on a flange 74 formed in the pedestal. Between the plate 73 and the sleeve 72 is carried a compression spring 75 which normally tends to lift the stem 70 and hold the stem in its highest position.

A link 76 is provided connecting the lower end of the stem to the lever 60, by which the stem is drawn down and the spring 75 is compressed. When the lever 60 is released, the spring 75 expands and pushes the stem 70 up. It pushes the shoe up against the heating pad 50 and holds it there with sufficient force to mold the sole to the shape of the shoe and secure the proper heating effect. The springs 49 are compressed to varying extents so that the cemented surfaces are brought together firmly throughout the whole area. While this pressure is on the heating pad 50 will be bent to conform to the shape of the pad 43 and the shape of the sole.

Pivotally mounted on the inside of the pedestal is a cylinder 77, in which slides a piston carried on the link 78. The piston compresses the air in the cylinder 77 and acts as a shock absorber to keep the spring 75 from lifting the stem 70 too abruptly.

On top of the stem 70 is provided the jack 20, fastened on the stem 70 by a set screw 81. On one end of the jack is provided a hole or socket 82 shown in Figures 2 and 3. This slot or socket is adapted to receive the head of an eyescREW 83 that is fastened in the wood last 84 that supports the shoe 85. On the other end of the jack is provided a block 86 mounted to slide in the grooves 87, as shown in end elevation at the bottom of Figure 5. On the side is a handwheel 88 having a set screw thereon. By turning this handwheel the set screw is caused to lock the sliding block 86 in any desired position. The block 86 is provided with two upright holes therein 90, 90 which are not threaded. In either of these holes can be placed the stud 91, on which is threaded the handwheel 92 which rests on the block 86. By turning the handwheel 92, the stud 91 can be raised or lowered to any desired position. On top of this stud is a block 93 having a groove 94 therein. This block is shaped on top like a saddle, as appears in Figure 5. On top of this block is placed a rubber block 95 which has an extension on the bottom thereof dove-tailed in the groove 94 and by which it is

held in place in the block 93 and on which it can move laterally or transversely. This block is tapered from front to back as is shown in Figures 3 and 4.

5 The stud 91 is adjusted so that it will hold the toe of the shoe up with the sole of the shoe to be cemented in position approximately parallel with the cushion pad 50, and then the pawl 65 is released from the ratchet 67 and the spring 75 is allowed to expand and push the sole of the shoe up against the pad 50. In so doing, the pad 50 will be bent to conform to the shape of the shoe as defined by the last in the shoe and as defined by the ultimate shape of the bottom of the pad 43. The springs 49 will be compressed in so doing, so that a sufficient pressure will be distributed over the whole of the sole of the shoe. This pressure may not be uniform, but it will be ample in each part of the sole for the purpose.

20 It will be understood that under pressure the last and sole will yield the least and the two pads and springs will yield the most. As is shown at the right in Figures 3 and 4, the pad 43 is provided with one row of lugs 42B, which are extra high or long, and another row of lugs 42A, which are of intermediate height or length, so that the top of these lugs will hold the bottom of the springs normally under about the same compression as the springs in the middle of the pad are held. A separate lug is used for each spring, instead of making the whole pad extra thick at this place so that the thickness of the pad 43 itself will be uniform throughout and it will have the same flexibility at the right hand end as it will in the intermediate parts thereof.

25 With the shoe and sole in place with the surfaces properly coated with cement, the pressure is applied. The current is then turned into the heating coil 52 and the pad 50 will be heated thereby. The spring steel members 53 and 54 will conduct the heat along the pad and across the pad and distribute it evenly throughout the pad 50, so that the sole of the shoe will be evenly heated throughout and will therefore cause the 30 cement to set and fasten the sole on the shoe in the shortest time and most efficient manner.

35 In adjusting the apparatus for cementing the sole, the bearing head 15 is moved back or forth, as may be desired, so that the right hand end 50a of the rubber pad will engage in the recess that is provided in front of the heel of the shoe. This bearing head 15 slides freely in the grooves 13 and 14 and will remain in any position desired 40 while the pressure is being applied to the sole 45 of the shoe, or will even adjust itself to some extent to the desired position.

45 As shown in Figure 3, the pedestal 10 is hollow and contains an electrical thermostat control unit 100, which is coordinated with the heating pad 50. In this control is a thermostat blade having a resistance coil thereon through which passes the current that heats the pad 50. This heating coil on the thermostat blade is in series with a snap switch 101 through which the current goes to the heating element of the pad 50. This thermostat blade has been calibrated so that when the temperature of the pad has reached the desired point, the thermostat blade will bend far enough to cause the snap switch 101 to open. 50 When the thermostat blade has heated up to the desired point and has bent far enough, it can be assumed that the temperature of the pad 50 has reached the desired point for causing the cement 55 to set on the sole of the shoe, and then the

thermostat blade 109 and the snap switch 101 act to open the circuit and prevent the temperature of the pad 50 from going higher. In this way overheating of the sole and of the cement is avoided.

For the purpose of controlling the supply of current furnished to the heating unit of the head, I use the electrical connections shown in Figure 14. As shown in Figure 14, terminals 105 and 106 are used to supply the current from an ordinary 110 volt line. From the terminal 105 the current flows through the line 107, and through a toggle switch 108, and through the resistance coil on the thermostat blade 109 which is heated by the passage of the current.

This thermostat blade bends as it is heated, and the free end of it makes contact with the small push button 110 on the snap switch 101. When the big push button 111 is pushed to the left, the small push button 110 on the other side of the snap switch is pushed to the left. When the blade 109 heats up, the end of it pushes against the push button 110 and moves it to the right, and the mechanism in the snap switch 101 releases the button 111, which is moved to the right, opening the circuit and stopping the flow of current to the heating unit.

The block 101 is a commercial unit made by the C. F. Burgess Laboratories, Inc., Freeport, Illinois, and formerly of Madison, Wisconsin, and is referred to as a Micro switch. This unit is a modification of the snap switch shown in Patent 1,960,020, issued May 22, 1934 to McGall, and constitutes no part of my invention. The unit is marked with Patent Number 1,960,020.

The movement of the thermostat blade 109 is regulated by the adjusting screw 112, shown in Figure 3. By advancing this screw to the left from the position shown in Figure 3, the thermostat blade will be moved away from the button 110 and it must then heat up more before it has moved far enough to move the button 110 and throw the switch.

From the block 101 the current flows through the conductor 113 to the post 114. The heating unit 52 is connected to the posts 114 and 106. A lamp 115 is connected between the posts 106 and 114.

In the ordinary operation, after the shoe is in position and the head 23 is brought down thereon, the operator pushes the button 111 to the left, which closes the switch. The operator then turns the switch 108 and the current begins to flow through the heating unit and at the same time the lamp 115 lights up and the light thereof shines through the red lens 116. After the thermostat blade has become heated up to a certain extent, it bends and presses on the button 110 sufficiently to cause the mechanism in the block 101 to open the circuit and push out the button 111, it being understood that the device operates as a snap switch. Until the circuit is broken, the current passes through the heating unit 52 and raises the temperature of it, and after the circuit is broken no more electric energy is furnished to the heating unit and thereafter it begins to cool off.

The setting of the thermostat blade determines the length of time that the current flows through the heating unit and fixes the temperature to which it rises, and the extent to which the cemented sole is heated thereby, it being understood that the temperature should be limited to about 130 degrees Fahrenheit. The length of time during which the cemented sole is exposed to this

heat should be limited to about 15 minutes, although experience may increase or decrease the time of the heating effect and the temperature used.

5 In Figure 11 I have shown an end view of the head 23, viewed from the right in Figures 2 and 3. In this view the normal position of the heating pad 50 and the rubber cushion plate 43 is shown, it being understood that this is the position that the parts occupy when the head is raised and the parts are not pressing against the shoe.

10 In Figures 12 and 13 I have shown a rubber cushion plate that is a modification of the form shown in Figure 6. As shown in Figures 3 and 6, the lugs 42 have a flat top, while in Figures 12 and 13 the corresponding lugs 125 are rounded on the top. In the open space in the middle of the cushion plate I provide a rib 126, which gives extra strength to the center of the pad.

15 Men's shoes are usually made with a Good-year welt, and this is also true of some women's shoes and children's shoes. The welt is used so that the sole can be attached to the shoe by sewing it to the welt. If the sole is cemented to the shoe sewing is unnecessary, but it so happens, that the welt overhangs the last and will not be supported thereby firmly enough so that the welt and the edge of the sole can be firmly held together under pressure. To support the welt so that it will stand up when pressure is applied to the sole, I provide the special form of welt support shown separately in Figure 17 and shown applied to a welt shoe in Figures 15 and 16. This 20 welt support comprises two short links 130 and 131, placed parallel to each other. Between the opposite ends of these links are pivoted the arms 132 and 133, the pivots being located at 134 and 135. Each of these arms comprises a long extension 136 and 137 on one side of the pivot, which is adapted to engage under the welt, and a short extension 138 and 139 on the other side of the pivot.

25 Pivotedly mounted between the two links 130 and 131 is a stud 140, around which is provided a helical compression spring 141, which is located between the short arms 138 and 139. Bearing against this compression spring is a sleeve 142, which is provided with grooves 143 on the opposite side thereof in which the short arms 138 and 139 engage. On the outer end of the stud 140 a wing nut 144 is threaded. By turning this nut the sleeve 142 is forced to the left, as shown in each of the Figures 15, 16, 17, and 18, compressing the spring 141. As this sleeve is moved to the left it reacts on the short arms 138 and 139, forcing them apart and drawing together the long arms 136 and 137 so that they engage closely under the welt. These arms are not only curved, as shown in Figure 17, but are beveled toward the left hand end as shown in Figure 19, so that the beveled edge can engage between the welt and the upper of the shoe and firmly seat itself against the edge of the last contained in the shoe, and thus firmly support the welt so that it will not yield to the pressure on the sole during the cementing operation. Pivotedly mounted on the arms 136 and 137 at 145a and 145b are the supporting blades 145 and 146, which blades can be swung inwardly from the position shown in Figure 17 to the position shown in Figures 15 and 16, in which position they engage between the upper and the welt and add additional support to the welt at the shank of the shoe where

the welt cannot be advantageously engaged by the arms 136 and 137.

On the outer ends of the arms 136 and 137 extensions 147 and 148 are pivoted. These extensions are supported by the pivots 147a and 148a. The ends of these extensions are connected by a helical spring 149, which spring is permanently attached to the end of extension 147 and is adjustably attached to the extension 148. The extension 148 is provided with a series of openings 150, 151, and 152, connected by narrow slots. On the end of the spring 149 is a button which can engage in either one of the openings 150, 151, or 152. This button has a small stem that engages in the opening 150, 151, or 152, by which it holds itself in place in either of the openings. By lifting the stem of the button out of the opening the button and spring can be moved from one opening to another, and will then lock itself in place by engaging the stem of the button with the next opening. In this way the tension of the spring 149 can be increased or diminished so that it will fit snugly around the toe of the shoe and will support the welt at the toe of the shoe, and will also serve to hold the extensions 147 and 148 in firm engagement with the welt.

This welt support is put in place as follows: The wing nut 144 is screwed back so as to give free play to arms 136 and 137. The spring 149 is placed in position on the toe of the shoe, and the arms are then brought into place between the welt and the upper, and the links 130 and 131 are swung up behind the heel of the shoe, and the wing nut is then screwed forward, causing the various parts to take a firm hold on the shoe 35 that will hold the welt in place against pressure.

1 claim:

1. In an apparatus for cementing soles on shoes, a jack for supporting the shoe in inverted position, a pedestal placed opposite said jack, a block mounted to slide laterally on said pedestal, and an inverted head mounted to swing up and down on a horizontal pivot on said block and adapted to engage with the sole of the inverted shoe, said bearing block being mounted to slide back and forth on the pedestal to bring the head into proper contact with the sole of the inverted shoe.

2. In an apparatus for cementing soles on shoes, the combination of a pedestal, a block on said pedestal, a head mounted to swing on said block, a plurality of recesses in said block, a pin sliding in the head adapted to engage with one or the other of said recesses for the purpose of holding said head in an up or down position, and a lever on the free end of the head for drawing said pin out of a recess and moving said head.

3. In an apparatus for cementing soles on shoes, the combination of an inverted swinging head, a horizontal pivot on which said head is mounted to swing, a block supporting said pivot on which said head swings, and a counterbalance spring interposed between the head and the block, said spring being adapted to swing the head upward.

4. In an apparatus for cementing soles on shoes, the combination of a jack for supporting a last with a shoe thereon in an inverted position, an inverted hollow head mounted to swing on a horizontal pivot, said pivot being opposite the jack and at one end of the head, said head extending over said jack, said pivot being held against up and down movement, means for locking said head in either an up or down position, and a single means for raising the jack with a 75

straight up and down movement and pushing the heel and toe of last with the shoe into the head when the head is in its down position.

5. In an apparatus for cementing soles on 5 shoes, the combination of an inverted hollow head, a flexible plate having heating elements therein placed adjacent to the rim of the hollow head, a cushion plate placed over the flexible plate, and a plurality of springs placed over the 10 cushion plate and between the cushion plate and the head, a horizontal pivot at one end of the head held against up and down movement on which pivot said head is mounted to swing with the head and cushion plate in an inverted position.

6. In an apparatus for cementing soles on 15 shoes, the combination of an inverted hollow head, a flexible plate having heating elements therein placed adjacent to the rim of the hollow head, a cushion plate placed over the flexible plate, a plurality of springs placed over the cushion plate and between the cushion plate and the head, and a marginal plate fastened to the lower rim of the head for the purpose of holding and heating unit, and the cushion plate in place 20 in the head.

7. In an apparatus for cementing soles on 25 shoes, the combination of an inverted hollow head mounted to swing on a horizontal pivot, a flexible plate, a resistance wire in said plate for the purpose of heating the plate, and flexible metallic strips in said plate for the purpose of spreading the heat formed in the resistance wire uniformly throughout the plate.

8. In an apparatus for cementing soles on 30 shoes, the combination of an inverted hollow head mounted to swing on a horizontal pivot, a flexible plate fastened in the rim of said head, a resistance wire in said plate for the purpose of heating the plate, and flexible and parallel metallic strips in said plate extending both lengthwise and transversely in said plate for the purpose of spreading the heat formed in the resistance wire uniformly through the plate.

9. In an apparatus for cementing soles on 35 shoes, the combination of an inverted hollow head mounted to swing on a horizontal pivot, a cushion plate fastened therein, lugs on said cushion plate extending up into the hollow head, and helical springs positioned with their lower ends on said lugs and having their upper ends bearing against the head, said head having sides that extend down around the margin of the cushion plate and also having an in-turned portion holding the cushion plate in place in the 55 head.

10. In an apparatus for cementing soles on 60 shoes, the combination of an inverted hollow head, a horizontal pivot at one end of the head on which it is mounted to swing, a cushion plate fastened in said head, lugs on the inside of the head extending down toward the plate, and lugs on the plate extending up toward the head, and helical springs positioned between the cushion plate and the head and centered on the lugs of the plate and of the head, said head having sides that extend down around the margin of the cushion plate and also having an in-turned portion holding the cushion plate in place on the 65 head.

11. In an apparatus for cementing soles on 70 shoes, the combination of a jack adapted to hold the heel and toe of the last in inverted position, said last having a shoe thereon placed on said jack, a screw on the rear end of the last having

an eye thereon engaging with an opening in the jack, a block on said jack supporting the toe of the last and means for raising and lowering said block on said jack, said means being movable forwards and back on the jack and a single means for raising the jack.

12. In an apparatus for cementing soles on shoes, the combination of a jack adapted to hold a last in inverted position, said last having a shoe thereon placed on said jack, a projection on the rear end of the last engaging with an opening in the jack, a block on said jack supporting the toe of the last and supporting means for raising and lowering said block on the jack, said means being movable backward and forward on the jack, said block being movable transversely on said supporting means.

13. In an apparatus for cementing soles on shoes, the combination of a hollow head, a flexible plate having heating elements therein extending across said hollow head, a cushion plate placed over the flexible head, a plurality of springs placed over the cushion plate and between the cushion plate and the head, and a marginal plate fastened to the lower rim of the head and extending inwardly therefrom for the purpose of loosely holding the heating unit and the cushion plate in place in the head and per-

mitting the flexible plate and the cushion plate to yield bodily into the head under pressure.

14. In an apparatus for cementing soles on shoes, the combination of a hollow head, a flexible plate having heating elements therein extending across said hollow head, a cushion plate placed over the flexible head, a plurality of springs placed over the cushion plate and between the cushion plate and the head, and a marginal plate fastened to the lower rim of the head and extending inwardly therefrom for the purpose of loosely holding the heating unit and the cushion plate in place in the head and permitting the flexible plate and the cushion plate to yield bodily into the head under pressure, means for supporting the sole of the shoe from the inside of the shoe, and means inserted between the welt of the shoe the upper of the shoe from the outside of the shoe for supporting the welt therefrom on opposite sides of the shoe, means for drawing said supporting means together, said welt supporting means and the parts associated therewith being free to rise and fall inside of the head with the sole of the shoe and the flexible plate and the cushion plate as pressure is applied.

JOSEPH AMICO.
